UNITED STATES PATENT OFFICE.

MARCUS T. GOLDSMITH, OF NEW YORK, N. Y.

MIRROR.

SPECIFICATION forming part of Letters Patent No. 760,981, dated May 24, 1904.

Application filed March 11, 1904. Serial No. 197,630. (No model.)

To all whom it may concern:

Be it known that I, MARCUS T. GOLDSMITH, a subject of the Czar of Russia, and a resident of the city of New York, borough of Manhattan, in the county and State of New York, have invented a new and Improved Mirror, of which the following is a full, clear, and exact description.

The invention relates to hand-mirrors; and its object is to provide a new and improved mirror arranged to require no special fastening devices for the bezel employed, to hold the silvered glass in place, and to give the mirror a very fine appearance.

15 The invention consists of novel features and parts and combinations of the same, as will be more fully described hereinafter and then pointed out in the claim.

20 A practical embodiment of the invention is represented in the accompanying drawings, forming a part of this specification, in which similar characters of reference indicate corresponding parts in all the views.

Figure 1 is a face view of the improvement. 25 Fig. 2 is a cross-section of the same on the line 2 2 of Fig. 1. Fig. 3 is a face view of the improvement, showing the bezel partly in position; and Fig. 4 is a cross section of the same on the line 4 4 of Fig. 3.

30 In hand-mirrors as heretofore constructed and having a frame formed with a back and a rim rising integrally from the back it has been customary to fasten the reflecting-glass in position by a split bezel, having fastening devices for securing the bezel in position on the rim. It is evident that the bezel has to be larger in diameter than the reflecting-glass to reach under the annular flange extending integrally from the top of the rim downwardly 35 on the inside of the rim, so that the bezel abuts against the under side of this flange and rests on the top of the usually-beveled edge of the reflecting-glass. Now in order to place such a bezel in position under a flange less in diameter than the bezel itself it was necessary to split the bezel to allow the operator to move the ends of the bezel inward past each other to reduce the diameter of the bezel sufficiently for the workman to spring the bezel in position under the flange and on top of the bevelled

edge of the reflecting-glass. Now when this had been done the bezel was opened to its full diameter until the split ends abutted, and in order to hold the opened-up bezel in position an arm was employed on one of the split ends for covering the split and for fastening the bezel to the flange at the inside to hold the bezel in place. Now such split bezel and its arm rendered the mirror very unsightly. With my improvement, presently 60 to be described in detail, a bezel of unbroken continuity is employed and placed in position and held therein without any arm or similar fastening devices whatever.

The frame A of a mirror, made of cast 65 metal—such as silver, britannia metal, and the like—consists, essentially, of a back A', from which rises an annular rim A², provided at its top with an inwardly and downwardly turned annular flange A³, as plainly illustrated in 70 the drawings. A handle A⁴ also extends from the rim A² to enable the user to conveniently manipulate the mirror for its legitimate purpose. The silvered glass or other reflecting-body B is of a diameter somewhat less than 75 the diameter of the annular flange A³ to allow of placing the reflecting-body B in position in the rim, preferably with its silvered back resting on a suitable lining C, of paper or other flexible material. 80

A bezel D of unbroken continuity—that is, in the shape of a ring and made of a flexible material—is engaged with the beveled edge B' of the reflecting-body B and is extended under the lower edge of the flange A³ for the bezel 85 to abut with its outer edge against the inner surface of the rim A², as plainly shown in Fig. 2. In order to place the bezel in this position, the operator after the reflecting-body B is in 90 position slightly bends the bezel, so as to allow of readily working the bezel gradually under the lower edge of the flange A³ until the portion D' of the bezel extends quite a distance upward above the top of the flange A³ and the reflecting-body B, as plainly indicated 95 in Figs. 3 and 4. When this stage of the operation has been reached, the operator uses a suitable tool, such as a short wooden stick or the like, and presses on the top of the raised portion, so as to gradually work this portion 100

D' under the flange A³, it being understood that the flexible end of the bezel permits such manipulating of the bezel by the workman, until the bezel is finally sprung under the 5 flange A³ and firmly rests all around on the beveled edge B' of the reflecting-body B.

The outer edge of the bezel D abuts against the inner surface of the rim A², and consequently the bezel cannot accidentally pass out 10 of position, especially as the flexible back or lining C has a tendency to press the reflecting-body B forwardly to insure a firm contact of the bezel with the beveled edge B' of the reflecting-body and with the lower edge of 15 the annular flange A³.

By the arrangement described no special fastening means whatever are employed for placing and holding the bezel in position, and by having the bezel presenting an unbroken 20 continuity on the face of the mirror it is evi-

dent that the appearance thereof is not impaired, but, on the contrary, greatly enhanced.

Having thus described my invention, I claim as new and desire to secure by Letters Patent—

A mirror having a frame formed with a 25 back and an annular rim rising integrally from the back, the latter having an integral, inwardly and downwardly extending continuous flange, a reflecting-body in the said frame, of less diameter than the said flange, and a bezel 30 of unbroken continuity, engaging the said reflecting-body at its edge and extending outwardly under the said flange, as set forth.

In testimony whereof I have signed my name to this specification in the presence of two sub- 35 scribing witnesses.

MARCUS T. GOLDSMITH.
